UNITED STATES PATENT OFFICE.

ROBERT D. McMANUS, OF HARTFORD, CONNECTICUT, ASSIGNOR TO JAMES McMANUS, OF SAME PLACE.

SHOE-BLACKING HOLDER AND REST.

SPECIFICATION forming part of Letters Patent No. 365,696, dated June 28, 1887.

Application filed December 4, 1886. Serial No. 220,737. (No model.)

To all whom it may concern:

Be it known that I, ROBERT D. McMANUS, of Hartford, in the county of Hartford and State of Connecticut, have invented a certain 5 new and useful Improvement in Shoe-Black- 5: ing Holders and Rests, of which the following is a full, clear, and exact description, whereby any one skilled in the art can make and use the same.

10 My improvement relates to the class of devices ordinarily called "blacking-cabinets," that are provided with means for supporting the foot and for holding the blacking and brush generally used in cleaning and polishing shoes.

15 The object of my improvement is to provide a device of this general class that is of more convenient form and adaptable for use in narrower or more confined places than prior devices; and to this end my invention consists 20 in a back plate with means whereby it may be attached to a vertical wall or like part, in combination with adjustable or folding shelves or brackets that are adapted to hold the black- 25 ing and to support the foot, and in details of the several parts and their combination, as more particularly hereinafter described, and pointed out in the claims.

30 Referring to the drawings, Figure 1 is a perspective view of the device, showing the foot-rest and blacking-bracket extended for use. Fig. 2 is a view in vertical section of the device, showing the position and arrangement of the parts when not in use.

35 In the accompanying drawings, the letter *a* denotes the back plate as a whole, that may be of any convenient material, preferably of metal, cast to shape with lugs *a'* and *a''*, that project forward and are adapted to hold between them, in one instance, the blacking-bracket *b*, and in the other the foot-rest *c*. The back- 40 plate is also provided with holes in the main portion of the plate or in projecting ears, through which nails or screws may be driven 45 for the purpose of securing the back plate to any structure and in a vertical position. The bracket *b* has a socket of any convenient form in which to secure a box of blacking, *d*, while the shank of the bracket is provided with a

slot, *b'*, and through which a pivot-pin passes, 50 while another pin or lug secured between the ears *a'*, and nearer the back plate than the pivot of the bracket, affords a stop, so that when the bracket is lifted to a level position and slid back this pin or lug *b'* prevents the 5: bracket from falling until it has been pulled forward.

The foot-rest *c* is hinged or pivoted to the back plate, so as to be folded back into a practically vertical position near the plate, and to 60 this rest is pivoted a brace, *c'*, that may have a limited opening movement by the contact of the bevel *c''* on its end striking the under side of the rest. The brace projects downward at an angle, with its outer end in contact with 65 the wall or like structure below the base-plate, so that the foot-rest is held firmly extended. The back plate may be of sufficient length to afford a resting place for the end of this brace, or a separate socket or bearing-plate may be 70 secured to the wall below the back plate to hold the end of the brace while the foot-rest is ex- tended.

A bottle-socket, *e*, may be formed in the upper part of the plate and adapted to hold a 75 bottle of liquid blacking or shoe dressing in a place convenient for use. When not in use, the bracket *b* and foot-rest *c* may be turned back into a vertical plane, and the blacking- 80 brush *f* held by thrusting the end of the han- dle *f'* back of the pivot and upper end of the 85 foot-rest, as shown in Fig. 2 of the drawings.

The methods of using this device are so obvious as not to need extended description.

I may of course vary the form and arrangement of my improved holder and rest without departing from my invention, and I do not limit myself to the particular form and relative ar- 90 rangement of the parts herein described.

I claim as my improvement—

1. In combination with the back plate, *a*, having the bracket-support or lugs *a'*, the folding foot-rest *c*, pivoted thereto, and having a space between its pivot end and the back plate to receive the handle of a blacking-brush, 95 all substantially as described.

2. In combination with the back plate, *a*, having the lugs *a'*, with the stop *b'* arranged

between them, and having also the lugs or bracket-supports a^2 , the blacking-bracket b , with slot b' , through which the pivot-pin passes to secure it to lugs a' , and the foot-rest 5 c , pivotally secured to the back plate, all substantially as described.

3. The improved blacking holder and rest, consisting of a back plate with a folding foot-

rest, the folding blacking-bracket, and a bottle-socket, all substantially as described, and 10 for the purpose set forth.

ROBERT D. McMANUS.
